UNITED STATES PATENT OFFICE.

FREDERICK C. BAKER, OF PORTLAND, OREGON.

DESIGN FOR A COMBINED NUTCRACKER AND BOWL.

60,394.

Specification for Design.

Patented Feb. 14, 1922.

Application filed February 28, 1921. Serial No. 448,606. Term of patent 14 years.

To all whom it may concern:

Be it known that I, FREDERICK C. BAKER, a citizen of the United States, residing at Portland, in the county of Multnomah and State of Oregon, have invented a new, original, and ornamental Design for a Combined Nutcracker and Bowl, of which the following is a specification, reference being had to the accompanying drawing, forming part thereof.

The figure in the drawing shows a per-

spective of my design. The essential feature of my design is the representation of a squirrel or similar animal holding his fore paws as if supporting a nut and feeding on the same, and the tail curled up, and a bowl base.

I claim:

The ornamental design for a combined nutcracker and bowl as shown and described.

FREDERICK C. BAKER.
